UNITED STATES PATENT OFFICE.

JOSEPH HILL, OF WINDOM, MINNESOTA.

AEROPLANE-BOMB.

1,302,554.

Specification of Letters Patent. Patented May 6, 1919.

Application filed August 7, 1917. Serial No. 184,900.

To all whom it may concern:

Be it known that I, JOSEPH HILL, a citizen of the United States, residing at Windom, in the county of Cottonwood and State of Minnesota, have invented certain new and useful Improvements in Aeroplane-Bombs; and I do hereby declare the following to be a full, clear, and exact description of the invention, such as will enable others skilled in the art to which it appertains to make and use the same.

The invention relates to an aeroplane bomb.

The object of the present invention is to improve the construction of aeroplane bombs and to provide a simple, practical and efficient aeroplane bomb adapted to carry a relatively large quantity of high explosives and of insuring a positive discharge of the same. It is also an object of the invention to provide an aeroplane bomb of this character which will, when dropped from an aeroplane, accurately maintain its course and thereby increase the effectiveness of bombs of this character.

With these and other objects in view, the invention consists in the construction and novel combination of parts hereinafter fully described, illustrated in the accompanying drawing and pointed out in the claim hereto appended; it being understood that various changes in the form, proportion, size and minor details of construction, within the scope of the claim, may be resorted to without departing from the spirit or sacrificing any of the advantages of the invention.

In the drawing:

Figure 1 is a longitudinal sectional view of a bomb constructed in accordance with this invention.

Fig. 2 is a horizontal sectional view on the line 2—2 of Fig. 1.

Like numerals of reference designate corresponding parts in the several figures of the drawing.

In the accompanying drawing, in which is illustrated the preferred embodiment of the invention, the aeroplane bomb comprises in its construction an outer shell 1 of relatively thin material provided with a tapered front or lower portion 2 and having its upper or rear portion 3 substantially cylindrical. The shell or casing, which presents the configuration of a bullet or projectile, may be constructed in any suitable manner to enable the interiorly arranged parts to be conveniently assembled, and the said shell,

which may be sectional, is provided at its front tapered portion with a solid projectile section 4 having a central longitudinal opening 5 which registers with an opening 6 in 60 the point of the shell 1.

Within the cylindrical opening 5 is arranged a tube 7 designed to contain a charge of dynamite and adapted to be exploded by a cap 8 which is discharged by the inward 65 movement of the said tube. The upper end of the opening 5 is threaded to receive a threaded disk 9 which is provided with a central tapered projection 10 adapted to form a firing pin and explode the cap 8. The 70 tube is provided at the lower end with a solid projecting portion 11 which is adapted to come in contact with the ground or other surface in the path of the bomb for causing inward movement of the tube. The shell is 75 equipped at the opening 6 with relatively flat springs 12 which embrace the tube and retain the same in position within the opening 5. The springs are designed to be of sufficient strength to prevent accidental dislodgment 80 or movement of the tube and they are adapted to permit the tube to be readily forced inward when the solid portion 11 comes in contact with the ground. The solid portion 11 and the tube constitute a plunger for 85 firing the cap. In practice, the tube is designed to be of sufficient size to contain about five pounds of dynamite, but the bomb may be varied in size as will be readily understood, and the upper portion 3 of the shell is 90 designed to contain a charge 13 of nitro-glycerin or other high explosive.

The shell is provided at the center of its top or rear wall 14 with a blade or vane 15 preferably consisting of a triangular sheet 95 of aluminum or other suitable material secured within a frame 16 of steel or other suitable material. This will cause the bomb to maintain a straight course and enable it to be dropped with accuracy. When the 100 bomb is dropped the solid portion of the tubular plunger will come in contact with the ground or with an object in the path of the bomb and the dynamite will be exploded and will cause an explosion of the nitro-glycerin or other high explosive. As the lower tapered or pointed portion of the bomb is heavier than the upper portion, the plunger will be maintained in proper position for contacting with the ground, building or other 105 object. The top wall 14 is provided with a filling opening 17 and it has a threaded

closure plug 18. This will enable liquid nitro-glycerin to be readily introduced into the upper portion of the shell but the shell may be charged in any other desired manner, 5 and the explosive may be in any desired form.

What is claimed is:

In a projectile, a cylindrical casing containing a main explosive charge, a downwardly tapering solid member secured to the 10 lower end of said casing and forming a closure therefor, said member being provided with an axial bore, a disk secured in said bore adjacent the upper end thereof and provided with a central downwardly directed 15 firing pin, a hollow cylindrical detonator

slidable in the bore of said solid member so as to be detonated by the firing pin when forced upwardly in said bore, said detonator being provided with a solid end portion projecting beyond the solid member carried by 20 the casing, and means frictionally engaging said detonator for releasably securing the same in operative position.

In testimony whereof I affix my signature in presence of two witnesses.

JOSEPH HILL.
